2 SHEETS—SHEET 2.

UNITED STATES PATENT OFFICE.

WILLIAM A. KILMER, OF DE KALB, ILLINOIS, ASSIGNOR TO THE AMERICAN STEEL & WIRE COMPANY OF NEW JERSEY, OF HOBOKEN, NEW JERSEY, A CORPORATION OF NEW JERSEY.

CLOSING DEVICE FOR ELECTRIC CIRCUITS.

1,220,342.

Specification of Letters Patent.

Patented Mar. 27, 1917.

Application filed January 2, 1914. Serial No. 809,915.

To all whom it may concern:

Be it known that I, WILLIAM A. KILMER, a citizen of the United States, and resident of De Kalb, in the county of Dekalb and State of Illinois, have invented certain new and useful Improvements in Closing Devices for Electric Circuits, of which the following is a specification.

My invention relates to fence fabric making machinery and has particular reference to a novel shear actuating device for use in connection with such machines and specifically such a machine as shown in my co-pending application, Serial No. 793,580, filed October 6, 1913, and my prior Patent 1,076,831, co-pending with my aforesaid application.

In the operation of fence fabric machines such as disclosed in my co-pending application referred to, the fabric is sheared into the required lengths by automatic means; that is, predetermined lengths such as ten rods, twenty rods, etc., are sheared without attention on the part of the operator it being understood that the required length is predetermined and suitable change gears installed. However, in many instances short lengths are required, that is, lengths down to a few feet for use in concrete reinforcements. To provide gears which may be changed to secure such uneven lengths would be impossible. I have therefore provided mechanism as shown on the inclosed drawings by means of which exact lengths may be provided the mechanism therefor being simple and as the actuation is electric, may be placed at any suitable distance from the machine. Broadly stated, the invention consists in an endless chain having one or more lugs or flights thereon, which lugs are adjustable in the length of the chain, these lugs acting upon suitable contacts, which contacts in turn close electric circuits and actuate a solenoid through which the shear clutch is operated.

My invention further consists in the use of means whereby a circuit is closed and an electric warning is given just prior to the actuation of the shear clutch.

50 The invention will be more readily understood by reference to the accompanying drawings, wherein,

Figure 1 is an elevation of a portion of a fabric machine having my novel shear actuating mechanism applied thereto;

Fig. 2 is a plan view of the endless contact operating device and its associated parts;

Fig. 3 is a side elevation of the same;

Fig. 4 is a fragmentary detail of the two contact pieces, and,

Fig. 5 is a side elevation of the same.

Referring more particularly to the drawings it will be seen that in Fig. 1, I have shown a portion of a fabric forming device, a specific description of which will not be made herein reference being had to my co-pending application heretofore referred to. In such mechanism there is provided on a constantly moving shaft 10, a sprocket 11. A chain 12 connects this sprocket to a shaft 13, carrying a beveled gear 14, which gear meshes with a similar gear 15, on a shaft carrying a suitable sprocket with which a chain 16, engages, this chain causing constant rotation of the endless chain 17, mounted on the sprockets 18, 19. On the chain 17 are provided lugs 20, as best shown in Fig. 2, spaced a suitable distance to provide for shear actuation to sever suitable lengths of fabric. The sprocket 18 is pivotally mounted on a shaft 22, which shaft likewise serves as a support for a disk 21, having pins 23, 23', upon one face and lugs or projections 30, 30', upon the opposite face, the pins and likewise the lugs being disposed diametrically opposite; that is to say, the pin 23' is located diametrically opposite to the pin 23 and the lug 30 is located diametrically opposite the lugs 30'. By providing two lugs 30, 30', upon the face of the disk adjacent to the chain 17, one thereof is certain to be within the arc of movement of a pin 20 carried by the chain as it travels around the sprocket and consequently the disk is moved 180° each time a pin 20 passes around the sprocket. With the lug 30 in the position shown in the drawings, the pin 23' is so positioned as to be about to engage the arm 24, although the pin 23 is some distance from the arm 25. The first movement of the disk will, therefore, cause a rotation of the arm 24 about its pivot 24'.

The contact piece 26 is likewise pivoted at 24', the angular end portion of the arm 24 bearing against the contact piece 26. A spring 28 serves to hold the parts in the relation shown in Fig. 4, although permitting the rotation of the arm 24 about the pivot 24' while the contact piece 26 remains station-

ary. Motion imparted to the arm 24 by the pin 23' will, through the agency of the spring 28, move the contact piece 26 into engagement with the stationary contact 5 26' and complete the circuit 31, whereby an electric light is energized, or, if preferred, a bell may be rung. This serves as a warning that the shear is about to be actuated. During the continuance of the 10 warning action, the pin 23 is traveling until it contacts the arm 25, whereupon, due to the coöperation of contact 27 and spring 29, which are duplicates of those just described except that they are reversely positioned, 15 the contact piece 27 is moved to close the contact against the stationary member 27' and the circuit 32 is closed, which serves to actuate the shear clutch. After the pin 23' has traveled in an arc to the point where the 20 end of the arm 24 may escape the same, the arm 24 will snap back, due to the action of the spring 24^a and the contact will be broken quickly as required in order to avoid arcing. The same action will follow the contact of 25 the pin 23 and the arm 24 under the action of the spring 25^a. When one operation is complete, the disk and contact members will be left in the position shown in the drawings, ready for engagement by another 30 pin 20.

It is obvious that the construction shown is only typical of other constructions which might be evolved therefrom and I do not therefore wish to be limited to the exact 35 form herein shown and described.

I claim:

1. In a device of the class described, the combination of machine elements and an endless chain driven by said elements, lugs 40 on said chain, a loosely mounted rotatable disk adapted for engagement with said lugs, projections on said disk, a signal circuit and an operating circuit and a switch for controlling each of said circuits, said switches 45 being located in proximity to the projections on said disk, the projections and switches being so located as to cause closing of said signal circuit before closing said operating circuit, substantially as described.
- 50 2. In a device of the class described, the

combination of machine elements, an endless chain driven by said elements, lugs removably secured to said chain, a disk having at least two lugs and so located that one of said last named lugs is certain to be engaged by 55 one of said lugs on said chain during substantially 180° of movement around a center, a plurality of switches controlling a plurality of circuits, projections on said disk, said switches and projections being so positioned as to cause actuation of said switches during substantially 180° of movement of said disk, substantially as described.

3. In a device of the class described, the combination of an endless chain, a plurality 60 of lugs removably secured to said chain, a disk having a plurality of lugs on one side and a plurality of projections on the other side, a plurality of switches adapted for actuation by the projections on said disk, the 65 projections on said disk and said switches being so arranged as to cause actuation of said switches in sequence and to cause said switches to be actuated during substantially 180° of movement of said disk, substantially 70 as described.

4. In a device of the class described, the combination of an endless chain, a sprocket around which said chain is caused to travel, a wheel mounted on the same center with 80 said socket and independently rotatable relatively thereto, at least two lugs on one side of said wheel and at least two projections on the other side of said wheel, a plurality of lugs removably secured to said chain and 85 adapted to contact the lugs on said wheel in sequence, a signal circuit and an operating circuit, switches controlling said circuits and located in proximity to the projections on said wheel, whereby said switches are 90 caused to be actuated in sequence and both said switches are caused to be actuated by a rotation of said wheel of substantially 180° under the action of one of the lugs on said chain, substantially as described.

WILLIAM A. KILMER.
